UNITED STATES PATENT OFFICE.

MATTHIAS C. SCHMIDT, OF TACOMA, WASHINGTON.

SHOE.

1,284,934.

Specification of Letters Patent. Patented Nov. 12, 1918.

Application filed August 30, 1916. Serial No. 117,569.

To all whom it may concern:

Be it known that I, MATTHIAS C. SCHMIDT, a citizen of the United States, residing at Tacoma, in the county of Pierce, 5 State of Washington, have invented certain new and useful Improvements in Shoes, of which the following is a specification.

This invention relates to shoes and especially to the form, proportion and shape of 10 the sole and heel.

The objects of this invention are to provide a shoe which will prevent the arch of the foot from being broken down; to relieve a person whose arch is broken; to permit the 15 gradual reestablishment of an arch after it has been broken; and to establish an arch in a flat foot. A further object is to accomplish these results without adding to the weight or complexity of the shoe and to render the shoe more flexible and therefore 20 easier on the foot.

I attain these and other objects by the devices, forms and arrangements illustrated in the accompanying drawings, in which—

25 Figure 1 is a section of my improved shoe, showing a foot therein and showing the foot bones within the foot, the shoe being in the position in which it is suspended or is just touching the ground with all weight removed therefrom;

Fig. 2 is a similar view showing it in corresponding position when weight is applied to the foot;

Fig. 3 is a side elevation of the same shoe;

Fig. 4 is a side elevation of a slight variation thereof, the heel being undercut to a further degree;

Fig. 5 is a side elevation of a second variation thereof, the heel being low; and

40 Fig. 6 is a view, similar to Fig. 2, showing a shoe such as is in common use and illustrating its tendency to break the arch.

Similar letters and numerals of reference refer to similar parts throughout the several 45 views.

The cause of a broken arch in a foot of normal shape is found in the shoe. Referring to Fig. 6, which illustrates such a foot in a common shoe, it will be seen that when 50 the leg is vertical the line of pressure falls forward of the front line of the heel of the shoe. When the leg is in this attitude it is supporting its greatest load and this load is

transmitted through the arch to the heel and to the toes. It is evident that in these 55 circumstances the lower portions of the joints of the bones of the arch have to be held against separation by the tension of the ligaments, as indicated by the opposed arrow-heads in the drawing, and that in 60 case of an overstrain or an inherent weakness the said ligaments will give way and the arch is lowered and broken. When this condition once occurs it largely destroys the use of the foot and occasions intense pain; 65 further, the weight of the body then comes on that unsupported part of the shoe in front of the heel with the result that the foot slips forward and the strain is still further increased by the relative withdrawal of 70 the shoe heel from the line of strain.

Now, examining the form of the sole and heel of such an ordinary shoe it will be observed that two conditions are always present:—first, the line of the lower surface of 75 the heel is in the same plane as the lowest point of the sole, so that when the shoe is on the ground (with or without weight therein) the sole touches and the heel engages the ground along its entire length; 80 and second, the heel is placed at the extreme rear edge of the shoe and does not extend forward more than 25% of the length of the shoe. One effect of the first mentioned condition is to deprive the shoe of all springiness as its form is not changed when pressure is applied to it or is removed therefrom.

Referring now to the other figures of the drawing, especially to Figs. 1 and 2, it will be seen that my improved shoe varies from 90 the common shoe in each of the above features. First, the plane of the lower surface of the heel lies below the lowest point of the sole, so that if the heel is in entire contact with the ground and there is no 95 weight in the shoe (Figs. 3 and 4) the sole is raised off the ground, but so that when pressure is applied to the foot the toe part of the sole is lowered into contact with the ground (Fig. 2). The result of this arrangement is that when the toes are brought down the front of the heel is relatively raised thus producing a pressure on the instep. It will also be noted that this downward motion of the toe must bend the unsupported part of the sole in front of the 100 105

heel so that when pressure is thus applied to the foot this part has a sharper bend in it than when it is unstrained. The effect of this is to extend forward that portion of the shoe on which the foot contacts (Fig. 2) and distribute the said weight or pressure over a larger area of the foot and thus somewhat reduce the intensity of the pressure at any one point. If the shoe has no pressure in it, it assumes a position shown in Fig. 1 in which the shoe contacts with the ground along the front edge of the heel and the lowest point of the sole, but, when pressure is applied thereto, the rear 15 of the heel and the front of the toe pass downward into the positions shown in Fig. 2, the heel of the foot tending to slide rearward, as indicated by the arrow on the heel bone in Fig. 1, and the front part of the 20 shoe heel pressing up under the instep.

Second, the heel of my improved shoe is pushed forward until its front line is positioned about 33% to 35% of the length of the shoe forward of the back line there- 25 of, and the rear of the heel is undercut from the rear of the sole so that in a man's shoe its rearmost point on its under surface is from 20% to 33% of the heel length forward of said back line, the proper amount 30 of said undercut depending on the degree of breakdown of the arch; and in a lady's shoe the said amount of undercut may be increased for appearances, the front line of the heel remaining in the position indi- 35 cated above.

The effect of this arrangement is two-fold, first, the front of the heel is brought forward of the line of strain from the leg; and second, undercutting the rear of the 40 heel brings the supporting surface only under the bones of the foot instead of extending well to the rear as is usual.

Now, when the effect of the forward-pushed heel is combined with the effect of the difference between the planes of the heel and sole, as above pointed out, we produce a condition which brings an upward pressure on the sole of the foot at a point forward of the angle when the weight is applied thereto (Fig. 2) and this pressure tends both to hold the heel in the rear of the shoe and also to raise the bones of the arch between the angle and toe, thus relieving the lower ligaments of all tension 50 and, if anything, causing a tension in the upper ligaments, as illustrated by the opposed arrow-heads in the said Fig. 2. Then, since the arch is relatively raised by the pressure, the leg muscles pull up on the 55 bones of the arch and thus the defective arch, whether a broken normal arch or a natural deformed arch or flat foot, is gradually repaired and becomes normal, or nearly so.

65 In carrying out the foregoing principles

I have developed certain variations which may be made in the depth of the heel and in the extent of the rear undercut. In Figs. 1, 2 and 3 is shown the standard form of my improved shoe, suitable for ordinary 70 cases of strained arch, in which the front line C of the heel 1 is forward of the rear line A of the shoe a distance equal to one-third of the distance between the line A and the front line E of the shoe. Also, the 75 lowest point D of the sole 2 is positioned about one-third of the height of the heel above the plane of the heel. Also, the back line B of the heel is undercut forward of the line A about one-fourth of the distance 80 between the lines C and A.

In Fig. 4 the shoe is varied only by chang- 85 ing the undercut line B to one-third of the distance between the lines C and A. This shoe is adapted to down-broken and flat- footed insteps.

In Fig. 5 the shoe is varied from that shown in Fig. 3 in that the heel is lower and is slightly thicker at its front line F than at the rear, thus inclining it downward relatively to the line of the sole over the heel. In this case the rear of the heel and the lowest point of the sole are in a plane sub- 90 stantially parallel with that of the sole over the heel but the front of the heel is slightly lower than said plane. In this case the rear line G of the heel is undercut one-fifth of the 95 distance between the lines F and A.

It is evident from the foregoing descrip- 100 tion that the two points on which I lay par- ticular stress are, first, the location of the front of the heel forward of the ankle or about one-third of the shoe length forward of the rear thereof; and second, the plane 105 of the heel lying below the lowest point of the unstrained sole so as to produce an up- ward pressure under the arch. The other features admit of variation to suit partic- 110 ular cases and conditions, namely the heel may be varied in thickness and the ex- tent of the undercut portion may be varied.

Having described my invention, what I claim is:

1. A shoe, having every point throughout the extent of its sole disposed wholly above 115 the plane of the lower face of the heel when said shoe is placed with its heel in contact throughout its extent with a horizontal sur- face and the shoe is relieved of all extraneous weight and strain.

2. A shoe, having the front line of the heel forward of the line of leg pressure, and the plane of the lower surface of the heel up- 120 wardly and rearwardly inclined, when the shoe is placed on a horizontal surface with the forward end of the heel and the middle portion of the sole in contact with said sur- face, the shoe being relieved of extraneous weight and strain.

3. A shoe having a sole and a heel, the 125

plane of the lower surface of the heel lying below the lowest point in the unstrained sole; and the front contact line of the heel lying wholly substantially one-third of the 5 shoe length forward of the rear of the shoe.

4. A shoe having a sole and a heel, the plane of the lower surface of the heel lying

below the lowest point in the unstrained sole; the front contact line of the heel lying wholly substantially one-third of the shoe 10 length forward of the rear of the shoe; and the rear of said heel being materially undercut.

MATTHIAS C. SCHMIDT.
